To all whom it may concern:

Be it known that I, Kenneth R. Lung, a citizen
of the United States of America, residing at Ken-
dallville, Noble County, Indiana, have invented
a new, original, and ornamental Design for Wind-
mills, of which the following is a specification,
reference being had to the accompanying draw-
ing, forming part thereof:

Fig. 1 is a side elevation view of a windmill em-
bodying my new design.

Fig. 2 is a perspective view thereof.

The essential feature of the design is shown in
full lines.

I claim:

The ornamental design for a windmill sub-
stantially as shown and described.

KENNETH R. LUNG.
